MATCH BOOK DISPLAY STAND

Joseph Shapiro, St. Louis, Mo., assignor to Universal Match Corporation, St. Louis, Mo., a corporation of Delaware

Application April 19, 1950, Serial No. 9,331

Term of patent 14 years

(Cl. D80—9)

To all whom it may concern:

Be it known that I, Joseph Shapiro, a citizen of the United States, residing at the city of St. Louis, State of Missouri, have invented a new, original, and ornamental Design for a Match Book Display Stand, of which the following is a specification, reference being made to the accompanying drawing forming a part thereof.

The figure is a perspective view of a match book display stand showing my new design. The side opposite to that seen in the figure is the same as the side shown and the end not seen is plain.

I claim:

The ornamental design for a match book display stand, substantially as shown and described.

JOSEPH SHAPIRO.
